UNITED STATES PATENT OFFICE.

SOPHIE MARGARET WITT, OF BENICIA, CALIFORNIA.

GAME APPARATUS.

1,031,157.

Specification of Letters Patent.

Patented July 2, 1912.

Application filed March 2, 1912. Serial No. 681,126.

To all whom it may concern:

Be it known that I, SOPHIE MARGARET WITT, a citizen of the United States, residing at Benicia, in the county of Solano and State of California, have invented certain new and useful Improvements in Game Apparatus, of which the following is a specification, reference being had to the accompanying drawings.

10 This invention relates to new and useful improvements in game apparatuses, which are adapted to play games of that class termed geographical games, and the objects of my invention are to provide an improved 15 game apparatus of this class which may be played by one or more persons, and which in addition to creating interest and affording amusement, will serve to educate or instruct the minds of the players as to the geographical 20 location and arrangement of the most important cities in the various countries.

Another object of the invention is to provide a game apparatus of this character 25 which will possess advantages in points of efficiency and durability, is inexpensive of manufacture and at the same time is simple in construction and operation.

With the above and other objects in view 30 the invention consists in the novel features of construction and the combination and arrangement of parts hereinafter more fully described, pointed out in the claims and shown in the accompanying drawings, in 35 which:—

Figure 1 is a plan view of the game board, showing thereon a map of the United States, having ten of the most important cities printed in heavy type; Fig. 2 is a view similar to Fig. 1, showing the map of Germany thereon; Fig. 3 is a perspective view of one of the dice shown in color to correspond with the color of the board in Fig. 1; and Fig. 4 is a perspective view of another die shown 45 in color to correspond with the color of the board shown in Fig. 2.

Similar numerals refer to similar parts throughout the several views.

In carrying out my invention, I employ a 50 suitable flat board or base member 1, which may be of any desirable material and upon this base member is secured a sheet of paper or other material 2 upon the upper face of which appears in colors or otherwise, a geographical 55 map. In the drawing the maps of the United States and Germany are used

for the purpose of illustration, although it is obvious that such maps might represent any country desired.

In the drawings I have shown but one die 60 to each of the two countries, but it will be understood that I prefer to use ten dice and ten of the most important cities in each country, although a greater or less number may be used if desired.

65 The game may consist of any number of maps of various countries and in each country ten of the most important cities are printed in heavy type to distinguish them from the other cities. The boards on which the maps are placed are distinguished by the use of various colors, thus it will be seen from viewing the drawings that the board on which the maps of the United States are placed will be red and the board on which Germany is shown will be blue, other countries may be distinguished by various chosen colors.

70 To each of the countries I provide the dice 3, ten dice being used to each country. 80 Each die is provided with six faces 4 and on one of these faces the name of one of the ten most important cities, in each of the countries, is printed, leaving the other five faces of the die blank.

85 Taking the United States for the purpose of illustration it will be seen that the ten most important cities to be used in the United States are indicated by heavy type as shown at 5. The board on which the map is placed is to be of any desired color but for the purpose of illustration the color red is used. To each map or country I provide ten of the dice which are of the same color as the board on which the map is placed, 90 thus red dice will be used with the map of the United States. On one of the six sides of each of the dice is printed one of the names of the ten cities illustrated by heavy type on the map leaving the other five sides 95 of the die blank as shown at 4.

100 The game can be played by two or more persons, each player taking one map, and ten dice of the same color as the board on which the map is shown.

105 In shaking the dice any desired form of dice box may be used. The first player takes the box, shakes the dice and throws them out on the table and if any of the names of the cities, printed on one face of each of the 110 dice, appear on the upper most faces of any of the dice, the die is placed on the name of

the city, which appears on the die, on the map. Thus if New York is shown on the uppermost face of one of the dice, the die is to be placed on the large dot on the map 5 indicating the city of New York. The second player shakes his dice and proceeds as the first player and so on until one of the players has all ten cities on his map covered by the dice bearing the names of the respective 10 cities, the player then calls out the name of the country appearing on his map, as, "United States wins."

If on examining the map of the winning player, a die is found misplaced the player 15 loses and cannot play until someone else wins and the next game is started.

It will be understood that I do not want to limit myself to the two countries herein shown and described but desire to use as many 20 countries as I wish, using ten dice to each country. It will be also understood that I do not wish to limit myself to any ten particular cities in each country but may pick out such cities as desired, nor do I 25 wish to limit myself to any particular number of cities in each country, but reserve the right to use any number I desire.

While I have shown and described the preferred form of my invention it will be 30 obvious that various changes in the details of construction and in the proportions may be resorted to for successfully carrying my invention into practice without sacrificing any of the novel features or departing from 35 the scope thereof.

Having thus described my invention, what I claim is:—

1. In a game, the combination with a board 40 having a map thereon illustrating one of the nations of the earth, and cities indicated on said map, of a plurality of playing pieces

each having one of the cities on the map designated on one of the faces thereof.

2. In a game, the combination with a board having a map thereon illustrating one 45 of the nations of the earth, and a number of cities indicated on said map, of a plurality of dice each having one of the cities on the map designated on one of the faces thereof.

3. In a game, the combination with a board of a certain color, having a map thereon illustrating one of the nations of the earth, and a number of cities indicated on said map, of a plurality of dice of a color corresponding with the board, said dice each 50 55 having one of the cities on the map designated on one of the faces thereof.

4. In a game, the combination with a board of a certain color, having a map thereon illustrating one of the nations of the earth, and a certain number of cities indicated on said map, of a number of dice corresponding to the number of cities on the map, said dice being of a color corresponding 60 65 with the color of the board, and each having one of the cities on the map designated on one of the faces thereof.

5. A game apparatus embodying a board having a map thereon illustrating a portion of the earth's surface and also having displayed on said map in the proper relative geographical position, characters indicating certain definite points of such portion of the earth, and a plurality of playing pieces each having a character on one of the faces 70 75 thereof indicating one of said points.

In testimony whereof I hereunto affix my signature in the presence of two witnesses.

SOPHIE MARGARET WITTE.
